UNITED STATES PATENT OFFICE.

CHARLES TWINING, OF LOCUST POINT, NEW JERSEY.

SAFETY-RAZOR.

1,119,327.

Specification of Letters Patent.

Patented Dec. 1, 1914.

Application filed October 21, 1912. Serial No. 726,938.

To all whom it may concern:

Be it known that I, CHARLES TWINING, a subject of the King of Great Britain, and a resident of Locust Point, in the county of 5 Monmouth and State of New Jersey, have invented a new and Improved Safety-Razor, of which the following is a full, clear, and exact description.

The present invention relates to safety 10 razors and more particularly to that type of safety razor in which a relatively thin blade is clamped between a bed-plate having along its edge a toothed guard, and a clamp plate.

15 As is well known to those familiar with this type of safety razor, the cutting edge is positioned closely to the upper surface of the toothed guard, and in use there is a tendency for the lather to pack along the edge of the 20 blade and between it and the upper surface of the guard, and at times the edge will become clogged to such an extent that it requires the release of the clamp and a partial disassembling of the parts for the purpose 25 of cleansing the edge and guard of accumulations of lather before the operation of shaving can be completed, and in any event, in such razors as heretofore constructed in order to effect a thorough cleansing 30 after shaving, a more or less complete disassembling of the parts is necessary.

The object of the present invention is to provide means whereby accumulations of lather along the edge and guard may be 35 quickly removed without the necessity of disturbing the adjustment of the parts.

To the above ends, the present invention 40 consists of a safety razor in which the bed-plate is provided with a clearance groove adjacent the guard with interdental openings 45 leading from the guard to said groove, and further, of the devices and combinations of devices which will be hereinafter described and claimed.

45 The present invention is shown in the accompanying drawing, in which—

Figure 1 shows an isometric perspective view of the bed-plate and guard, and handle portion of one form of razor to which my 50 invention is applicable. Fig. 2 shows an end elevation of the parts of the razor assembled for use, the lower part of the handle and the clamping nut being broken away.

Similar reference characters will be employed 55 throughout the specification and drawing to designate corresponding parts.

The razor comprises a bed-plate 1, provided along its opposite longitudinal edges with toothed guards. Preferably, the bed-plate 1 will be rectangular in shape longer 60 than it is wide, and in the form of razor shown in the drawing, it will be provided with a guard 2 along each of its longitudinal edges and will be slightly curved or convexed transversely as shown clearly in Fig. 65 2. The bed-plate 1 is provided with a hollow cylindrical handle 3, and the blade 4 is supported upon the upper surface of the bed-plate 1 and clamped thereon by means of a clamping plate 5 which latter has a 70 threaded shank, not shown, which passes through an opening 6 and is received into the tubular handle 3 in position to be engaged by an interiorly threaded tubular clamping member which is adapted to be 75 inserted in the lower end of the handle 3 in a manner well known to those familiar with razors of the type shown. The clamping plate 5 has upon its under surface two depending studs 7, one of which is shown in 80 Fig. 2 of the drawing, which studs pass through openings in the blade 4 and through openings 8 in the bed-plate 1. By turning the tubular clamping member, the threaded shank of the clamping plate 5 will be drawn 85 downward, thus bringing the under side of the clamping plate 5 into forcible contact with the blade, and flexing or curving the blade and clamping it tightly against the upper surface of the bed-plate, as shown in 90 Fig. 2 of the drawing.

As shown clearly in Fig. 1, the upper surface of the bed-plate 1 is provided adjacent the row of teeth forming the guard 2 with a longitudinally extending clearance 95 groove 9, which groove extends through the ends of the bed-plate, preferably at each end as shown, and which along its outer edge coincides with the edge of the plate 1 which forms the base 10 of the interdental spaces 100 11 and thus the longitudinal groove 9 opens into the interdental spaces 11 by means of the interdental openings 12.

In the form of razor shown in the drawings wherein a double edged blade is used 105 and the plate 1 has a guard along its opposite longitudinal edges, there will be longitudinally extending clearance grooves positioned one adjacent to each of the guards.

By the foregoing arrangement, it will be 110 clear that when the parts are assembled as shown in Fig. 2 with the blade 4 tightly

clamped upon the bed-plate 1, the opposite edges of the blade 4 may be brought into close contact with the upper surface of the guard teeth 2, and that the accumulation of lather along the cutting edge of the blade and between the teeth of the guard may be quickly removed by water poured upon the edge of the guard, which water will flow through the interdental openings 12 into the longitudinally extending clearance groove 9, carrying with it the lather and other matter which may have accumulated along the cutting edge, and flowing out of the groove 9 at its opposite ends.

15 Where the invention is embodied in a double-edged razor such as shown, the parallel longitudinally extending clearance grooves 9 will preferably be connected by a transversely extending groove 13, and as shown in the drawing, there may be two transversely extending grooves 13 connecting the longitudinally extending grooves 9. By means of the transversely extending connecting grooves 13, the water used in cleansing may flow from one longitudinal groove to another and thus greatly facilitate the cleansing operation.

It will be observed that the interdental openings 12 permit the lather to pass beneath the edge of the blade into the longitudinal clearance groove, and thus the tendency of the lather to accumulate in the interdental spaces of the guard and along the edge is retarded, and such accumulations, as before stated, may be quickly removed without the necessity of disturbing the adjustment of the parts or disassembling them.

by the flow of water passing through the interdental spaces 12 and into the longitudinal clearance groove 9, the flushing action of the water effecting a complete clearance of all clogging lather.

It is to be observed that in forming the clearance grooves in the bed-plate, the portions of the bed-plate bounded by such grooves form blade supports along the longitudinal median line of the blade, and thus effectively support the flexible blade as the blade is flexed to cause it to conform to the curvature of the bed-plate.

Having thus described my invention, I claim as new and desire to protect by Letters Patent of the United States:

A safety razor comprising a bed plate having toothed guards along its parallel longitudinal edges, a blade, a clamping plate, the bed plate having parallel clearance grooves formed in its blade supporting surface adjacent the toothed guards, interdental openings connecting said clearance grooves with the openings in the guards, laterally extending connecting grooves and blade supports intermediate the clearance grooves, the blade spanning the interdental openings and engaging the teeth of the guards.

In testimony whereof I have signed my name to this specification in the presence of two subscribing witnesses.

CHARLES TWINING.
